UNITED STATES PATENT OFFICE.

ALICE JEANNETTE MILLER, OF CHICAGO, ILLINOIS.

DESIGN FOR A BENCH STANDARD.

Application filed March 26, 1928. Serial No. 26,012. Term of patent 3½ years.

To all whom it may concern:

Be it known that I, ALICE JEANNETTE MILLER, a citizen of the United States of America, residing at Chicago, in the county of Cook and State of Illinois, have invented a new, original, and ornamental Design for a Bench Standard, of which the following is a specification, reference being had to the accompanying drawing, forming a part thereof, and in which—

Fig. 1 is a front elevation of the article, showing my new design, and Fig. 2, an end elevation.

I claim:

The ornamental design for a bench standard as shown.

ALICE JEANNETTE MILLER.
